LAST

William H. Nutt, Beverly, Mass., assignor to
United Shoe Machinery Corporation, Paterson,
N. J., a corporation of New Jersey

Original application September 12, 1935, Serial
No. 40,287. Divided and this application Jan-
uary 21, 1937, Serial No. 121,625

4 Claims. (Cl. 12—139)

This invention relates to lasts, and more particularly to those adapted for use in the performance upon the heel-portions of shoes of such operations as the attachment of heels thereto. The present case is a division of an application for improvements in Means for operating upon the heel portions of shoes, filed in my name in the United States Patent Office on September 12, 1935, Serial No. 40,287.

10 In attaching heels, and especially those of wood, a recognized practice is to operate through a passage in the cone of a last within a shoe to be heeled, and when thus operating, to drill an opening through the heel-seat of the shoe into a heel clamped thereon, countersink the insole-material about the drilled opening, insert a screw in the last-passage, and finally set the screw in place with a screw-driver to draw the heel-seat and the cup of the heel together. An adhesive 20 is customarily applied between the attaching surfaces. Difficulties are encountered in such a procedure. The last-passage must be of sufficient diameter to admit the head of the screw. Because of the size of the passage and the consequent tendency of the drill and the point of the screw to enter the work out of correct axial alignment, it is desirable to have some centering means by which both are held in their true paths. An 25 object of my invention is to insure the correct positioning of the tools and of the fastening for insertion. To this end, I employ a last adapted to enter a shoe and position the work for the operations upon it, said last having a passage opening through the heel-seat-surface. The last-passage contains a fastening-centering device, 30 preferably provided with yieldable arms extending into proximity to the opening and arranged to be engaged by and to locate axially of the passage rotatable operating means, such as a drill and countersink by which the heel-seat and heel are prepared to receive a screw-fastening and a screw-driver by which said fastening is inserted in the work, and to similarly locate the fastening itself. The centering device is shown as mounted 35 in the last-passage and held against displacement by a last-thimble, as through one or more projections from the centering device, these projections either entering depressions in the last-thimble or extending between the end of said thimble and a sleeve threaded into the opposite extremity of the passage.

The accompanying drawing illustrates a particular form of the invention, together with a modification thereof. In the drawing,

55 Fig. 1 is a central, vertical section through my

improved last, with drilling and countersinking tools partially inserted in the last-passage;

Fig. 2, a perspective view of a centering device or quill used in the last of Fig. 1;

Fig. 3, a broken perspective of the sleeve for 5 securing the quill in the last-passage;

Fig. 4, a view similar to Fig. 1 but showing screw-inserting mechanism associated with the last;

Fig. 5, a central, vertical, longitudinal section 10 through the heel-end of a last provided with a quill differing from that of the preceding figures;

Fig. 6, a perspective view of the quill of Fig. 5, and

Fig. 7, a similar view of the last-thimble by 15 which the quill is retained in place.

Referring to Figs. 1 to 4, a last 14 has extending vertically through its cone a passage which at its upper portion may be protected by a thimble 30. Threaded into the lower portion of the passage is a sleeve 32 (Fig. 3) of greater internal diameter than the thimble. Held between the adjacent extremities of the thimble and the sleeve are outward projections 34 from a tubular body 36 of a centering device for a screw or other fastening. As is best shown in Fig. 2, this device is in the form of a spring-quill, there being resilient arms 38, which may be three in number, depending from the body 36 in proximity to the heel-seat-opening of the last-passage. When the arms 20 are forced outwardly against the inside of the sleeve 32, the internal diameter of the passage between them is preferably substantially the same as that of the thimble 30. Another form of mounting for the quill appears in Figs. 5 to 7. 25 Here, a thimble 40 lines the entire last-passage and has in its wall openings or depressions 42. The quill has an extended body 44, a flange 46 of which lies at the top of the last-cone. Projections 48 are shown as struck out of the body, 40 these being inclined outwardly and upwardly toward the flange. They are so located that when the quill is forced into the last-passage until the flange bears against the top of the cone, the projections will spring into the openings 42 and lock 45 the elements together, as may be seen in Fig. 5. From the quill-body depend screw-engaging arms 50, which, when expanded, will have an internal diameter similar to that of the body 44, curved ends 52 of the arms then lying in a lower enlargement 54 of the thimble. In either form of the device, the lower ends of the arms converge downwardly and inwardly to normally approach relatively close to each other and, as illustrated in Fig. 4, so contact with the thread of a screw 55

that the point will be positioned substantially at the axis of the last-passage. The head of the screw enters the bore of the thimble of Fig. 4 and the body of the quill of Fig. 5 to move freely therethrough, yet with little lateral play. Therefore, when the screw is dropped into the last-passage, it will be so retained by the quill-arms that its axis and that of the passage practically coincide. Both the projections 34 and 48 retain 10 their respective quills 36 and 44 against displacement in the last-passage.

When a shoe S and a heel H are clamped between unillustrated supports for the tread-surface and the last 14, the heel-seat and heel are first 15 to be drilled to the proper depth to facilitate the insertion of a screw s and the heel-seat-material countersunk to receive the screw-head. This may be accomplished by the elements illustrated in Fig. 1. These consist of a drill 66, of the 20 proper diameter to produce a hole in the work to receive the screw, and an outer concentric sleeve or tube 76, the lower inclined end of which has cutting edges 78 furnishing a countersink. The drill and countersink-tube are so arranged 25 that the former is first rotatable to produce the opening for the attaching screw. Then, the rotation of the drill is communicated to the tube, which is driven to countersink the opening for the reception of the screw-head. The operator 30 introduces the tools 66 and 76 into the thimble 30 of the last 14 upon which the shoe S and heel H are clamped together. The countersink, having no initial driving force applied, upon contact with the arms 38 of the quill is held by these 35 against rotation and presses them back against the inner wall of the sleeve 32. As the force applied to the quill-arms is therefore only longitudinally thereof, without the rapid rotary effect which would be imparted by a driven tool, the 40 quill is but little affected and will require only infrequent renewal. Were the rotary contact permitted, the quill-arms would be subjected to much wear, and, if they were caught at the edges by the tool, might be torn off. The descent of 45 the tools will be stopped by the contact of the countersink with the insole of the shoe. When this is felt by the operator, he causes the drill to move through the countersink, which serves to center and guide it axially of the last-passage. 50 The drill will therefore enter the insole substantially at right-angles to its surface. The drill bores into the heel-seat-material and heel to the desired depth for the screw. At this time, the countersink will be driven and will produce a 55 depression in the heel-seat-material in which the head of the screw may lie, the drilling of the opening being simultaneously completed. The

rotation of the countersink-tube in contact with the quill may be very brief.

Having prepared the shoe and heel as just described, the operator drops the screw s point down into the last-passage (Fig. 4). Here, its 5 head will engage the wall of the thimble 30 with its lower threaded portion resting upon the quill-arms 38, it thus being axially aligned with the passage and with the drilled opening in the work. The point therefore cannot catch in the insole-material, and the slot in the screw-head will be properly positioned to receive a screw-driver which is to insert it. The spindle 116 of this screw-driver is surrounded by a sleeve 124 having the same external diameter as and rotatable 15 upon the spindle, it leaving only the bit of the screw-driver projecting. The sleeve 124 acts during the insertion of the screw-driver as did the countersink-sleeve 76, so that it is held against rotation by engagement with the quill-arms 38, 20 pressing these back without appreciable wear or distortion when the screw-driver-bit enters the slot in the screw and inserts it in the hole drilled in the heel. A like protection is afforded the quill upon the withdrawal of the screw-driver. 25

Having described my invention, what I claim as new and desire to secure by Letters Patent of the United States is:

1. In combination, a last having a passage opening through the heel-seat-surface, and a 30 fastening-centering device secured in the passage at the heel-seat-end and constructed and arranged to position substantially at the axis of the passage and at the heel-seat-surface the entering point of a fastening, the device being provided with a projection to retain it against displacement in the passage.

2. In combination, a last having a passage opening through the heel-seat-surface, a thimble situated in the passage and having a depression in its wall, and a centering device within the thimble and provided with a projection entering the depression. 40

3. In combination, a last having a passage opening through the heel-seat-surface, and a 45 centering device situated in the passage and provided with a lateral projection holding it against longitudinal displacement and with spring-arms converging toward the heel-seat-surface.

4. In combination, a last having a passage opening through the heel-seat-surface, a thimble situated in the passage at one extremity, a sleeve having threaded engagement with the passage-wall at the opposite extremity of the passage, and a centering device provided with a retaining portion clamped between the thimble and the sleeve. 55
